CLAIM

The ornamental design for a clinical analyzer as shown and described.

DESCRIPTION

FIG. 1 is a front, top and right side perspective view showing the cover open state of a clinical analyzer according to the design;

FIG. 2 is an enlarged view of the portion shown in box, labeled, "FIG. 2," in FIG. 1;

FIG. 3 is a front, top and right side perspective view thereof;

FIG. 4 is a front view thereof;

FIG. 5 is a left side view thereof;

FIG. 6 is a right side view thereof;

FIG. 7 is a top plan view thereof;

FIG. 8 is a bottom plan view thereof;

FIG. 9 is a rear view thereof;

FIG. 10 is an enlarged cross-sectional view taken along line 10-10 of FIG. 4;

FIG. 11 is a front view showing the cover open state thereof;

FIG. 12 is a cross-sectional view taken along line 12-12 of FIG. 11; and,

FIG. 13 is an enlarged view of the portion shown in box, labeled, "FIG. 13," in FIG. 12.

The dashed broken lines in the drawings show portions of the clinical analyzer that form no part of the claimed design. The dot-dash broken lines in the drawings indicate boundaries of the claimed subject matter that form no part of the claimed design. The dot-dot-dash broken lines in the drawings indicate boundaries of the view indicators that form no part of the claimed design.

1 Claim, 7 Drawing Sheets
